UNITED STATES PATENT OFFICE.

EDWARD HAROLD FOSTER, OF MOUNT VERNON, NEW YORK.

MOTOR-CYCLE STAND.

1,160,397.

Specification of Letters Patent.

Patented Nov. 16, 1915.

Application filed November 14, 1913. Serial No. 801,043.

To all whom it may concern:

Be it known that I, EDWARD HAROLD FOSTER, citizen of the United States, residing at Mount Vernon, in the county of Westchester 5 and State of New York, have invented certain new and useful Improvements in Motor-Cycle Stands, of which the following is a specification.

This invention relates to an improved motor-cycle stand or support.

The primary object of the invention is to provide suitable means carried by the motor-cycle frame for supporting the motor-cycle in a standing position.

15 A further object of the invention contemplates the provision of a novel and peculiar support wherein means is provided for laterally bracing and balancing the motor-cycle when starting or stopping, the support being so mounted as to be swung, after starting, into an inoperative position, and out of engagement with the ground.

20 The invention still further aims to provide means including supplemental bracing or balancing wheels, mounted for rotation independent of the drive wheel of the motor cycle, the said supplemental wheels serving the double purpose of balancing the machine, when starting or stopping, as above 25 set forth, and as a support or stand during repair or non-use of the machine.

The above and additional objects are accomplished by such means as are illustrated in their preferred embodiment in the accompanying drawings, described in the following specification and then more particularly pointed out in the claims which are appended hereto and form a part of this application.

30 In describing my invention in detail reference will be had to the accompanying drawings wherein like characters denote like or corresponding parts throughout the several views, and in which:—

40 Figure 1 is a side elevation of a portion of a motor-cycle illustrating the application of the invention thereto, the support or stand being swung into an inoperative position; Fig. 2 is a view similar to Fig. 1, the 45 device or support being illustrated in an operative position; Fig. 3 is a rear elevation of a portion of the device; Fig. 4 is a longitudinal sectional view of one of the supplemental wheel supporting arms; Fig. 5 is a 50 detail perspective view of a portion of the operating lever and the connecting rods as-

sociated therewith; and Fig. 6 is a detail view of one of the retaining elements, employed in connection with the present invention.

60 Before proceeding with the description of the drawings, I desire to call particular attention to the fact that while I have evolved my invention with particular reference to its application in connection with motor-cycles, the same may be readily utilized as a 65 stand or support in connection with bicycles, velocipedes and other two wheeled vehicles.

Referring now to the drawings wherein is illustrated the preferred embodiment of 70 my invention the numeral 1 designates a motor-cycle in its entirety having the usual fuel tank 2, engine 3, drive wheel 4 and rear axle 5 associated therewith. Pivoted to a collar 6 and fixedly secured to the frame 75 1 at a point, preferably, forward of the engine 3, as at 7, I provide an operating lever 8 the one end of which is provided with a handle 9 by means of which the said lever is actuated, and the opposite end pivoted as 80 at 10 to a connecting rod 11.

Detachably secured to the rear axle 5 of the drive wheel 4, the axle being suitably lengthened, and upon each side of the said rear wheel, I provide supplemental wheel 85 supporting arms designated as an entirety by the numeral 12, each arm comprising a rod member 13 having a head 14 formed upon one end thereof through which the said axle 5 extends. The free end of the said rod member 13 is inclosed within a suitable tubular sleeve member 15 the lower extremity of which is closed and enlarged as at 16 to provide for the mounting of a stub shaft 17 upon which one of the supplemental balanc-

90 ing wheels 18 is mounted for rotation, a nut 19 being threaded upon one end of the said shaft 17 to maintain the said wheel 18 in operative position. Between the lower extremity of the rod member 13 and the closed 95 end of the tubular member 15, and inclosed within the latter, I provide an expansion helical spring 20 of sufficient tension to elevate the rear wheel 4 of the motor cycle, during the operation of the stand or support, slightly above the ground or other surface upon which the machine is standing. 100 As a guide for the rod 13, and as a stop means therefor, a pin 21 extends transversely therethrough, the projected extremities of 105 the said pin fitting elongated apertures or slots 22 provided therefor within the 110

tubular member 6 in diametrically opposite relation. By the provision of a supplemental wheel 18 upon each side of the drive wheel 4, it is apparent that the motor cycle is braced laterally and balanced properly when not in use.

The opposite end of the connecting rod 11 from that connected to the operating lever 8 is pivoted as at 23 to a lug or projection formed integrally with the tubular member 15. This connection between the said operating lever 8 and one of the tubular members 15 provides for the operation of the latter, and, as it has been found necessary upon practical application of the invention, to simultaneously operate or actuate both wheels 18, a second operating rod 25 has been provided, the inner end of the said rod being pivoted as at 26 to a link 27 terminating at a point in axial alignment with the pivot point 7 of the said operating lever 8.

The link 27 is enlarged at one end to provide an extension, said extension being polygonal in cross section throughout a portion of its length, the said portion fitting a complementary opening therefor in lever 8 to provide for movement of link 27 and lever 8 in unison. The enlargement is tubular in cross section throughout a portion of its length, the last mentioned portion fitting an opening therefor in the vehicle frame. The detail formation of the enlargement is shown to advantage in Fig. 5, the said enlargement in the said figure being shown disconnected to better illustrate its construction. To maintain the said lever 8 in the position indicated in Fig. 2 of the drawings, I provide a retaining element 28 fixedly secured as at 29 to the tank 2 of the motor cycle at a convenient point thereupon, the said retaining element being disposed to overlap the said operating lever and thus provide a securing means therefor. If desired, a like element (not shown) may be provided at a point adjacent the forward end of the said tank 2 to maintain the said lever 8 in the position indicated in Fig. 1.

The operation of the device is as follows:—The support or stand being in operative position, it is apparent that the rear or drive wheel of the motor cycle is slightly elevated above the ground and the entire machine laterally braced and perfectly balanced to permit, if necessary, proper repair of the machine. To use the machine, it is not necessary that the wheels 18 be swung into inoperative position as is illustrated to advantage in Fig. 1 of the drawings until after the said machine is well under way, as the wheels 18, by reason of their independent mounting, are capable of rotation independent of the drive wheel 4, and, as is apparent, provide a lateral brace for the machine until swung into inoperative position by the manipulation of the operating lever

8. When under way, and it is desired that the said wheels 18 be rendered inoperative, the said operating lever 9 is removed from engagement with the retaining element 28 and swung upon its pivot 7 thereby actuating the arms 12 swinging the latter upon their pivotal connection provided by the axle 5 of the rear wheel and elevating the supplemental wheels carried thereby out of engagement with the ground. When it is desired that the machine should be brought to a stand still, without stopping the engine the lever 8 may be again actuated in a reverse direction, thereby swinging the said wheels 18 into engagement with the ground.

From the above, taken in connection with the accompanying drawings, it is further apparent that the rods 11 and 25 are actuated simultaneously by reason of the connection of the link 27 to the operating lever 8; that the arms 12 upon which the supplemental wheels 18 are mounted, are also actuated simultaneously by reason of the simultaneous movement of the said rods; and that the tension of the springs 20 is sufficient to elevate the drive wheel 4 of the motor cycle slightly above the ground during non-use or repair of the machine.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In combination, a velocipede, a support therefor comprising support rods having pivotal connection with the rear wheel axle, a tubular member partially inclosing each rod, each tubular member having diametrically aligned openings formed therein, lugs projecting from the respective rods to fit the respective openings therefor, a spring interposed between the closed end of each tubular member and the inclosed terminal of each rod, and a wheel carried by each tubular member, the respective springs forming a cushioning element for said wheels, and means having connection with the respective tubular members to bodily move the said support either into or out of engagement with the ground.

2. In combination, a velocipede, a support therefor comprising a pair of support rods having pivotal connection with the rear wheel axle, the rods extending in divergent

relation therefrom, a tubular member arranged to partially inclose the rods, a spring interposed between the closed end of each tubular member and the inclosed terminal 5 of each rod, lugs projecting from each rod at diametrically opposite points and fitting diametrically alined slots of the tubular member, a wheel carried by each tubular member, the respective springs forming a 10 cushioning element for the respective wheels, an operating lever having pivotal connection with the velocipede frame, a rod having pivotal connection with the lever, and direct connection with one of said tubular members, a second rod having direct connection with the other of the said members, said second rod extending parallel with said last mentioned rod, and a connection between the respective rods to provide for operation of said rods simultaneously through manipulation of the lever to move said support either into or out of engagement with the ground.

3. An attachment for velocipedes including a rod member pivotally connected to each extremity of the rear axle of the velocipede, a tubular member arranged to inclose the free end of each rod, each tubular

member having a pair of alined slots formed therein, a pin extending transversely of each 30 rod member fitting said slots, a spring arranged within said tubular member, the said spring being disposed for engagement with the said rod to form a cushion for the said tubular member, a supplemental wheel 35 mounted for rotation upon the free end of each tubular member, an operating lever pivoted to the velocipede frame, a rod connecting the said lever with one of the said tubular members, a link connected to the 40 said lever, a second rod connecting the said link with the other of the said tubular members, the two rods adapted to be actuated by the movement of the said lever to simultaneously actuate the two tubular members 45 to swing the said wheels into and out of engagement with the ground, and means for locking the said lever in its adjusted positions.

In testimony whereof I affix my signature 50 in presence of two witnesses.

EDWARD HAROLD FOSTER.
